UNITED STATES PATENT OFFICE

2,594,707

STATOR WINDING MACHINE

Ernest C. Allen, Rochester, N. Y., assignor to General Motors Corporation, Detroit, Mich., a corporation of Delaware

Application March 19, 1948, Serial No. 15,835

10 Claims. (Cl. 242—1)

1 This invention relates to a machine for winding stators used in the manufacture of alternating current motors.

It is an object of the present invention to provide a stator winding machine which can be adapted to wind stators of various sizes.

In the disclosed embodiment of the present invention, this object is accomplished by the combination with a fixed stator holder, to which the stator is attached, of a reciprocating shuttle which includes a portion which is rotary and through which a plurality of wires are threaded for winding a plurality of polar coils simultaneously. The reciprocating movements of the shuttle are obtained by a hydraulic servomotor which is automatically controlled so as to give at least the amount of reciprocatory shuttle movement required for the polar coils. The oscillation of the rotary portion of the shuttle is effected by a second hydraulic servomotor. The reciprocatory and oscillatory movements of the shuttle are precisely controlled by a series of cams sequentially cooperating with a cam follower operatively connected with the shuttle. A plurality of turn counters operate in sequence to determine the numbers of turns of the polar coils. The counters are adjustable to count out different numbers of coil turns. The cams are replaceable by other cams, the machine is adapted to support different stator holders and to operate different shuttles and the control of the reciprocation of the shuttle can be adjusted so that the machine can wind coils of different numbers of turns and different core-tooth spacing upon stator cores of different diameters, of different thickness and having different numbers of core teeth.

Further objects and advantages of the present invention will be apparent from the following description, reference being had to the accompanying drawings, wherein a preferred embodiment of the present invention is clearly shown.

In the drawings:

Fig. 1 is a perspective view of the machine embodying the present invention.

Figs. 2 and 3 together constitute a plan view.

Figs. 4, 5 and 6 together constitute a side elevation.

Fig. 7 is a plan view of a portion of the mechanism shown in Fig. 2, certain parts being in section and said section being taken on line 7—7 of Fig. 10.

Figs. 8 and 10 together constitute a sectional view on line 8—8 of Fig. 7.

Figs. 9 and 11 together constitute a view in the direction of arrows 9 of Figs. 8 and 10.

2 Fig. 12 is a view in the direction of arrow 12 of Fig. 13.

Fig. 13 is a sectional view on the line 13—13 of Fig. 10.

3 Figs. 14 and 15 together constitute a sectional view on the line 14—14 of Fig. 5.

Fig. 16 is a sectional view on the line 16—16 of Fig. 14.

10 Figs. 17 and 18 are sectional views taken respectively on lines 17—17 and 18—18 of Fig. 16.

Figs. 19 and 20 constitute a sectional view on the line 19—19 of Fig. 5.

Figs. 21 and 22 constitute a sectional view taken on the line 21—21 of Fig. 15.

Fig. 23 drawn to a larger scale than Fig. 29 is a plan view on the line 23—23 of Fig. 29 of the upper shuttle member.

15 Fig. 24 is a sectional view on the line 24—24 of Fig. 29 of the intermediate rotary shuttle member.

Fig. 25 is a sectional view on a larger scale than Fig. 29 of part 155 shown in Fig. 29.

Fig. 26 is a view of part 220 as viewed in the direction of arrow 26 of Fig. 29, Fig. 26 being drawn to a larger scale than Fig. 29.

Fig. 27 is a view in the direction of arrow 27 of Fig. 29.

Fig. 28 is a view in the direction of arrow 28 of Fig. 7.

Fig. 43 is a fragmentary sectional view on the line 43—43 of Fig. 42.

Fig. 44 is a view of parts 194 and 182 looking in the direction of arrow 44 of Fig. 43.

Fig. 45 is a fragmentary sectional view on the line 45—45 of Fig. 42.

Fig. 46 is a fragmentary sectional view on the line 46—46 of Figs. 14 and 49.

Fig. 47 is a plan view in the direction of arrow 47 of Fig. 46, showing bracket 305 and parts supported thereby.

Fig. 48 is a sectional view on the line 48—48 of Fig. 46.

Fig. 49 shows a portion of the mechanism shown in Fig. 14, right half.

Fig. 50 is a sectional view on the line 50—50 of Fig. 49.

Figs. 51 and 52 are sectional views taken respectively on lines 51—51 and 52—52 of Fig. 50.

Fig. 53 is a sectional view on the line 53—53 of Fig. 5.

Fig. 54 is a sectional view on the line 54—54 of Fig. 53.

Fig. 55 is a portion of the left side of Fig. 53.

Fig. 56 is a view in the direction of arrow 56 of Fig. 54.

Fig. 57 is a sectional view on the line 57—57 of Fig. 53.

Fig. 58 is a sectional view on the line 58—58 of Fig. 54.

Fig. 59 is a fragmentary sectional view showing a hinged construction.

Fig. 60 is a sectional view on the line 60—60 of Fig. 53.

Fig. 61 is a view in the direction of arrow 61 of Fig. 62.

Fig. 62 is a view in the direction of arrow 62 of Fig. 53.

Fig. 63 is a sectional view on line 63—63 of Fig. 53.

Fig. 64 is a sectional view on line 64—64 of Fig. 65.

Figs. 65 and 66 together constitute a sectional view on line 65—65 of Fig. 5.

Figs. 67 and 68 taken together constitute a view in the direction of arrow 67 of Fig. 5 with the hood 356 in section.

Fig. 69 is a chart of cams which control rotary movement of the intermediate shuttle member.

Fig. 70 is a hydraulic diagram of the machine.

Fig. 71 is a diagram of the wire unreeling device, wire tension and wire break safety switch.

Fig. 72 is a circuit diagram of the controls of the machine.

Fig. 73 is a front view of a counter with cover removed.

Fig. 74 is a rear view of the counter.

Fig. 75 is a diagram of a function of the counter.

The principal frame work of the machine comprises a base plate 30 (Fig. 1) attached to a base 30a, a front frame 31, a rear frame 33 and a top or table 32 supported by frames 31 and 33. The space between the front and rear frames is closed by panels 537, each having an opening closed by door 534, hingedly connected with the panel and stopping against strips 535 (Fig. 5).

Referring to Figs. 14, 19 and 21, the front frame 31 supports brackets 38 and 46 providing bearings for a shaft 5 which, as shown in Fig. 16, is drivingly connected with cams 13, 52 and 50 and a gear segment 15. Nuts 5a are screwed on the end shaft 5 in order to retain the parts. A pin 16a drivingly connects shaft 15 with a tube 16 to which gear segments 14 are attached. A spacer 17 is located between the left gear 14 and

the bracket 38. The cams 50 and 52 respectively operate switches LS4 and LS1 mounted on a plate 59 (Fig. 14) which is mounted on a bracket 51 attached to frame 31. Referring to Figs. 20 and 22, the base 30 supports a hydraulic cylinder 37 in which there is a piston 15c (Fig. 70) connected with a rod 15b (Figs. 19, 20 and 21) which provides a rack 15a (Fig. 21) which meshes with a gear segment 15. The rack 15a is reciprocated vertically to cause an oscillatory movement of gear segments 14 oscillate to cause vertical reciprocation of racks 171 and 203 which, as shown in Fig. 30, tie together frames 204 and 179 having bearing sleeves 202 and 198 respectively which slide on rods 194 and 167. The upper ends of these rods are received by holes in a plate 212 (Fig. 29) which screws 209 attach to the top frame or table 32. As shown in Fig. 30, the bottom end of rod 167 is received by bushing 177 press-fitted through a hole in the base 30 and through a hole in the reenforcing plate 171b welded to base 30. The lower end of rod 194 is received by a bushing 192 which screws 192a attach to the base 30, said bushing passing through a hole in a reenforcing plate 192b welded to the base 30. Bushing 192 is located by a dowel 192c passing through base 30 in plate 192b. The rod 194 is located with respect to the base by a key 192d received by a key-slot in the bushing 192. Thus the rod 194 is fixed in a definite angular position relative to the base 30.

As shown in Fig. 30, the frame 204 supports a non-rotatable lower shuttle member 153, supporting at its upper end (Fig. 29) a ball bearing 160b in alignment with a ball bearing 160a supported by the frame 204. These bearings rotatably support a shaft 166 connected, as shown in Fig. 30, with a gear segment 133 and with a lever 178, the shape of which is shown in Fig. 37. Bearing 160a is retained by a retainer 162 attached to frame 204. The lower end of shaft 166 is supported also by a ball bearing 160c which a plate 197 fixes to the frame 179. The lower end of shaft 166 carries a bushing 199 in alignment with the groove of a wire guide wheel 200 having the bearing bushing 200a journaled on a rod 210 which is supported as shown in Figs. 40 and 41, by brackets 159 having flanges 160 which screws 160a attach to the plate 191. The wires which are passed around the wheel 200 and upwardly through the shaft 166 are retained on the wheel by a roller 208 journaled on a pin 180 supported by brackets 159. Referring to Fig. 30, the sleeve 174 spaces bearing 160c from the lever 178. Sleeve 165 spaces lever 178 from the hub of gear 163. Sleeve 161 spaces bearing retainer 162 from 160b.

In Fig. 29, shaft 166 has a cup-shaped portion 166a which receives a wire guide 155 shown in larger scale in Fig. 25 and said cup-shaped portion 166a receives also the flange 153a of shaft 153. Shaft 153 supports the wire guide member 220 shown in larger scale in Fig. 26, said member having a stem 220a received by a central bore in the shaft 153. The cup portion 166a, the member 155 and the flange 153a are secured together as a unit by screws 153c. When these parts are assembled four wire guide passages are provided each passage comprising grooves 220a in part 220, grooves 153b in flange 153, grooves 166c in the cup-shaped portion 166a of the shaft 166 and holes 156a in wiper-shoes 156. For a four pole 36-slot stator core, there are four wiper-shoes 156 spaced 90° apart and 32 wiper-

5

shoes 216, as shown in Fig. 24. All of these shoes are received by the stator slots and operate to place the wires in the stator slots by a wiping action. The intermediate shuttle member includes the assembly of parts 153a, 166a, 155, 220 and shoes 156 and 216.

The upper shuttle member is provided by the tubular member 151 rotatably supported by ball bearings 222, the inner races of which engage the shaft 153. A tube 152 spaces the bearings 222. The upper bearing is retained by nut 224 threadedly engaging the upper end of shaft 153 and retained by a lock washer 223. The upper shuttle member 151 carries a plurality of wiper-shoes 148 of the same shape as the wiper-shoes 148 carried by the lower shuttle member 158 and the same shape as the wiper-shoes 156 and 216 of the intermediate shuttle member. The upper shuttle 151 carries a cap 146 having a cross slot 146a for receiving the blade 528a of a bar 528 pivoted on a pin 527 carried by bracket 524 having bearings 526 which slide on a rod 523 attached by a screw 521 to a bracket 520 supported by a table 32. A rod 522 connects bracket 524 with frame 204 (Fig. 30). Therefore, the bracket 524 moves with the frame 204, an upper position of the bracket being shown as 524' in Fig. 29. The bar 528 normally engages the cap 146 thereby preventing rotation of the upper shuttle member 151 and holding its shoes in alignment with the shoes of the lower shuttle member 158. Before placing an unwound stator core SC (Fig. 29) upon the work-holder 157, the bar 528 is moved to the position 528' in which position it is held by a spring detent ball 524b retained by the bracket 524 and urged into a recess provided by the bar 528.

As shown in Fig. 7, the workholder 157 is provided with four stator core receiving lugs 157a adjacent to which there are four slots 157s through which the wires are passed before being wound upon the stator core. The end of each wire is anchored to the table 32 by pressing it into the V-groove between the wire anchoring jaws 142 and 143 (Fig. 28), said jaws having inclined surfaces provided by serrations 142a and 143a which grip the wire as it is pressed down into the V-slot. Screws 144 secure the jaw 142 to the jaw 143 and screws 145 secure the jaw to the table 32. There are four pairs of these jaws, one for each of the four wires. The stator core SC is retained upon the four lugs 157a of the holder 157 by two clamping bars 221 attached to screws 218. Each screw 218 passes through a hole in a lever 213a pivoted at 213b on a bracket 213c attached to table 32. A screw 213d tightens the clamping end of the lever 213a about the screw 218 and the position of the screw 218 is determined by nuts 218a. A lever 213, pivotally attached to bracket 213c by pin 213a, is connected by pin 213f and a toggle link 213g with a pin 213h passing through the lever 213a. When the lever 213 is in the position shown in Fig. 29, the clamp 221 is forced against the stator core SC by toggle action. The work is unclamped by moving the levers 213 into the position shown in Fig. 1. The workholder 157, which screws 214 attach to plate 212, is connected by screws 194a (Fig. 7) and 167a with the upper ends of rods 194 and 167 respectively.

The four wires which are threaded through the shuttle and are anchored to the pairs of jaws 142, 143 are unwound from four spools, one being indicated at 610 in Fig. 71. The wire w passes through an eye 611 around wheels 612 and 613 75

6

between tension pads 614, around wheels 615 and 616 and around a wheel 70 (Figs. 19 and 20) which is journaled on a rod 69 supported by a bracket 71 attached to frame 32 which is behind frame 31 in Figs. 19 and 20. A rod 68 supported by bracket 71 retains all four wires in engagement with wheel 70. From wheel 70, the four wires pass into the machine through a hole 70a in plate 537 (Fig. 5) and then between roller 208 (Fig. 30) and wheel 200 and then upwardly through the shuttle shaft 166. Fig. 71 shows a mercury switch 606 mounted on a lever 617 pivoted at 618 and carrying a wheel 619 which engages the wire. There is a switch 606 for each of the four wires. When any wire breaks a switch 606 opens and the machine stops. This will be explained in detail later.

For a reason to be stated later, it is desirable to lock the intermediate spindle section against rotation during a certain part of the movement of the frames 204 and 179 vertically. This locking arrangement is shown in Figs. 42-45. The gear segment 163 attached to the shaft 166 is engageable by a locking dog 184 pivoted on a screw 186 attached to the frame 204. A spring 187 urges the dog 184 counterclockwise to engage a tooth space of the gear segment 163. It is possible for this to take place provided a ball 191 can be received by the groove 182a of a bar 182 which screws 182b attach to the rod 194. When the location of frame 204 is such that the ball 191 rides out of groove 182a upon the outer periphery of rod 194 the rod is caused to push against a pin 189 guided by the frame 204 and said pin is caused to push upon a pin 185 attached to the dog 184. Therefore, it is only during a limited intermediate travel of the frames 204 and 179 that the ball can be received by the groove 182a so that the gear 163 can be engaged by a dog 184 whereby rotation of the intermediate spindle section (including shuttle shaft 186) is prevented.

In other positions of frames 204 and 179, the shuttle shaft 166 can be rotated by mechanism 45 to be described for the purpose of angularly displacing the intermediate shuttle section in order to locate the wires in alignment with the proper slots of the stator core. The lever 178 (Fig. 30) attached to the lower end of shaft 166 has two radial grooves 178a (Fig. 37) for receiving rollers 126a attached to the arms of a lever 126 attached to a shaft 138 (Fig. 39) journaled in bearings 126b and 126c provided by the frame 179. Frame 179 and a bracket 128 attached thereto support bearings 133 which journal a shaft 136 attached to a lever 135 to which screws 132a attach to a gear segment 132 meshing with a bevel gear segment 126d provided by the lever 126. Lever 135 carries a stud 135a pivotally supporting a cam 60 follower roller 125b.

Roller 135b is adapted to cooperate in sequence with cams 274, 275, 276 and 277, 301, 397, 295 and 294 (Fig. 69) which are supported by a turret 296 (Fig. 46) which is attached to a shaft 312 journaled in bearings 269 and 303 supported respectively by brackets 272 and 305, the former being supported by the base 30 and the latter by the back frame 33. The turret is indexed by a mechanism which comprises a dial plate 273 attached by screws 345 and dowels 345a to the turret 296 and providing a gear 273a meshing with a gear 351 journaled on rollers 346 supported by a rod 347 extending from the cover 241 of a frame 271. The frame 27 (Fig. 52) houses bearings 321 and 327 serving as cylinders which receive a pis-

ton 323 extending through seals 324. The rod 323 provides a rack 323a meshing with a gear segment 333 carrying a pin 234 which pivotally supports a pawl 336 which a spring 341, bearing against a stud 337 (attached to segment 333), urges against a ratchet 334 secured by a pin 335 to a shaft 263. The shaft 263 is driven counter-clockwise as viewed in Fig. 52 by the pawl 336. When the gear segment 333 rotates clockwise, rotation of the shaft 263 is prevented by a spring 233 (Fig. 50) which wraps itself about the collar 231 pinned to the shaft 263 and a plug 232 which a pin 230 attaches to the frame 271.

The shaft 263 carries pins 264 (Fig. 50) journaling rollers 265 which successively engage a slotted Geneva gear plate 351a integral with gear 351 (Fig. 46). Therefore, for each movement of the rack bar 323 upwardly as viewed in Fig. 52, there will be a 60° rotation of member 351 clockwise and a 45° rotation of the dial 273 and the turret 296 counterclockwise.

While the turret 296 is stationary, it is locked by a bar 293 (Fig. 49) engaging a notch 273b in the dial 273. When indexing starts, the bar 293 is retracted from the dial against the action of a spring 294. The bar 293 slides in a groove provided by plate 291 which screws 286 attach to the member 241. The spring 294 is retained by a cover 287 attached to the member 291. Retraction of the bar 293 from the dial 273 is effected by counterclockwise movement of the shaft 263 whose head is provided with camming surfaces which engage a roller 261 supported by an arm 257a of a lever 257 pivotally supported by members 241 and 291. Lever 257 has an arm 257b adjustably secured to an arm 255a of a gear segment 255 which meshes with a rack 293a provided by the bar 293. The notches in the dial 273 are shaped to assist the latch 293 to become located. The cam 263 when rotating does not immediately move the dial due to the use of the Geneva motion. The roller 265 enters slot 351a at a tangent and therefore does not impart an immediate movement to the dial 273. The latch 293 does however, move rapidly out of the slots in the dial.

Referring to Fig. 52, the cylinders which are provided by the bushings 321 and 327 within which the bar 323 operates as a piston, are closed by caps 317 and 332 which are provided with pipe-tapped openings 317a and 332a respectively for receiving pipe connections. When the bar 323 is down as shown in Fig. 52, the oil passage through the threaded opening 332a is blocked by washer 331a which a screw 331 attaches to the lower end of bar 323. Similarly when the bar 323 moves up, the oil passage 317a is blocked by a stud 322 attached to the bar 323. Upward movement of the bar 323 as viewed in Fig. 48, is limited by a screw 315 engaged by the stud 322, said screw being locked by lock nuts 315a. A cap 319 is screwed to the cover 317 to protect the screw 315. The function of the screw 331 and the stud 322 is to retard discharge of oil from the cylinders provided by the bushings 321 and 327 near the end of the strokes of the rod 323 whereby movement of the turret is decelerated as it comes to rest.

Referring to Fig. 46, shaft 312 is drivingly connected with cams 306 and 310 for operating limit switches LS3 and LS2, respectively, which are supported by a bracket 316 supported by bracket 305. Shaft 312 drives a gear 308 (Figs. 14 and 21) meshing with a gear 27 journaled on a stud 25 which nuts 23 secure it together with a washer 24 to a bracket 26 supported by the table 32.

Bracket 26 carries a bearing bushing 312a (Fig. 14) which receives the upper end of the shaft 312. Bracket 26 carries a bushing 22 which receives the upper end of a shaft 21 which is attached to a gear 18 meshing with gear 27. Shaft 21 is supported at its lower end by bearing 92a in a bracket 92 (Fig. 64) attached to base 30. Shaft 21 drives two similar discs 20. The discs 20 support pairs of pins in alignment. These pins are of different lengths and determine the reversals of the vertical movements of the shuttle. The pairs of pins are automatically indexed into alignment with rack stop members 201 and 195 (Figs. 30 and 33) attached to the rack 203. As the racks move up, the stop 201 contacts the upper one of a pair of pins and, as the racks move down, the lower stop 195 contacts the upper end of a lower one of a pair of pins. The pins are of different lengths, for example, pins 55 are 2½" long, pins 56 are 3½" long, pins 54 are 4½" long and pins 53 are 5½" long. These pins are threaded into discs 20 and secured and adjusted in position by lock nuts 20a. The function of these pins is to determine at least the minimum requirements of shuttle stroke for each of the four polar windings of the stator. Whenever the turret has been indexed to locate a pair of winding control cams for engagement with the cam follower 135b, a pair of stop pins is located in alignment with the rack stops. Whenever the turret is indexed to present a transfer cam to the cam follower, the lower pins only are in alignment with the rack stop 195. Downward movement of stop 195 to engage a lower pin causes shaft 21 to move down (Fig. 64) and to cause a cam 83 to engage plunger 83a (Fig. 65) of a valve A which, in a manner to be described, causes reversal of movement of the piston in the cylinder 37 (Fig. 22) whereupon the rack 263 moves up to cause upward movement of the shuttle until stop 201 engages an upper pin and causes shaft 21 to move up and so to shift cam 83 as to cause valve A to reverse hydraulic connections so that the shuttle will move down again. When the upper stop 201 retracts from the upper pins and the lower stop 195 retracts from the lower pins, the shaft 21 remains in the position into which it had been moved before the retraction by virtue of brake shoes 85 supported by bracket 92 urged by springs 86 against the shaft, said springs being retained by plugs 87.

The function of the cams on the turret is to determine precisely the amplitude of reciprocations of the shuttle and the amplitude of oscillations of the intermediate shuttle member but is not to force rotation of the intermediate shuttle member. The tracking of the cam follower 135b with the crossovers of the cams is effected by a servomotor which will now be described. The frame 179 supports a cylinder 121 (Fig. 35) in which a rod 118 operates as a piston (Fig. 37). Rod 118 has a rack 118a which meshes with a gear 126e provided by the member 126. At each end of rod 118 a leather cup washer 228 is secured by a screw 226 which passes through a metal washer 227. Each end of the cylinder 121 is closed by a plug 229 which is grooved to receive seal rings 229a. Each plug 229 is attached to a cap 113 threadedly engaging the end of the cylinder and locked against rotation by a screw 113a. The cap 113 retains a swivel sleeve 115 having internal grooves receiving seal rings 114. Sleeve 115 is spaced by washer 116 from a nut 117 threadedly engaging the cylinder 121. The two nuts 117 are screwed against the two racks 171 and 203. Each

swivel sleeve 115 provides an annular groove 115a connected to the interior of cylinder 121 through passages 121a; and the groove 115a is connected with a pipe 111 attached to the sleeve 115. Referring to Fig. 34, each pipe 111 is connected with a swivel shaft 107 providing a duct 107a which is connected with a swivel sleeve 109 having internal grooves, each receiving a seal ring 109a. Sleeve 109 is retained by nut 103 threadedly engaging the member 107. Sleeve 109 provides an annular groove 109b in communication with the passage 107a and with a pipe 102 communicating with the passage 105a of a fixed swivel rod 105 which a screw 106 attaches to a bracket 34. Each of the fixed members 105 is provided with a pipe-tapped hole 105b by which a connection is made with the hydraulic system in a manner to be described. The function of the articulated pipes 102 and 111 is to conduct pressure fluid to one end or the other of the cylinder 121, during vertical movement of the racks 171 and 203.

After winding the stator core SC (Fig. 10), it is stripped from the shuttle by causing the hooks 418a on the lower ends of levers 418 to move under the stator core and then move upwardly. For this purpose the levers 418 are pivoted at 421 on brackets 422 supported by a floating ring 423. The upper ends of lever 418 are provided with slots 418b which receive pins 418c supported by brackets 427 welded to a plate 426 which a screw 431 and a nut 432 attach to a frame 437 which is slidable on vertical posts 441 supported by a housing 447 attached to the table 32. The ring 423 carries a bracket 424 (Fig. 11) supporting a pin 424a which pivotally supports a lever 445 having a hook 445a normally received by a notch 425a of plate 426. A spring 424b urges the lever 445 clockwise in Fig. 11. As the frame 437 begins to move up from the position shown in Fig. 10, the levers 418a so move that their hooks 418a move under the stator core SC and fingers 415 and 416 move against the core; and the stator is stripped from the shuttle by further upward movement of the frame 437. To release the wound stator from the stripping device, the operator pushes upwardly upon the under surface of the stator, thereby causing the ring 423 to move up relative to the plate 426 and thereby causing the hook 445b of lever 445 to engage upon the upper surface of the plate 426 thereby holding the levers 418 in such position that the hooks 418a are held retracted from the stator so that it can be lowered by the hand of the operator without interference by the hooks. During the winding of the stator, the frame 437 remains in an upper position so that the levers 418 are entirely above the shuttle in its uppermost position. Preparatory to stripping the next stator from the shuttle, frame 437 is lowered and the lever 445 is moved counterclockwise so that it is released from the plate 426 and the ring 423 can descend preparatory to the next movement of the levers 418 for engaging the underside of the stator core.

The frame 437 is moved by a compressed air servomotor comprising a cylinder 450 containing a piston connected with a piston rod 460 which is coupled by a screw 461 with a yoke 442 integral with a rod 442a which is in alignment with the rod 460. As shown in Fig. 8, rod 442a slides in a bearing 449 in a bracket 448 attached to the housing 447. As shown also in Figs. 8 and 9, the rods 441 pass through washers 428, which screws 428a attach to the housing 447 and the

upper ends of the rods receive screws 430 which retain washers 429. The housing 447 supports a rack 443 engaged by a gear 457 keyed to a shaft 451 journaled in roller bearings 455 supported by the yoke 442. There is a spacing sleeve 456 between the gear 457 and the left roller bearing 455. The shaft 451 is connected by keys 454 with gears 453 which mesh with racks 439 attached to the frame 437. Washers 452a and nuts 453a threaded on the ends of shaft 451 retain the parts as shown in Fig. 13. It is apparent, therefore, that movements of the piston in the cylinder 450 will cause vertical movements of the frame 437 at a rate greater than the rate of movement of the piston. If necessary the servomotor including the cylinder 450 may be aided by an auxiliary servo comprising a cylinder 450x in Fig. 1, whose piston is connected by rod 431x with the frame 437, said rod taking the place of screw 431 (Fig. 10) as a means for securing the plate 426 to the frame 437. The control of admission of compressed air to the cylinder or cylinders is effected by a valve 465 (Figs. 2 and 7).

Referring to Figs. 20 and 65, the piston rod 15b of the servo cylinder 37 carries a cam 63 secured by a clamp screw 62. Cam 63 cooperates with a roller 64 pivoted on a pin 65 carried by a lever 66 pivoted on a screw 67 supported by a bracket 72. As the rod 15b reciprocates the lever 67 reciprocates a plunger 73a of a pump 73 supported by a plate 75 carrying a seal-ring 74 surrounding the pump. Plate 75 is supported by an oil tank 77 supported by the base 30. A level gauge 80 is connected by a pipe 81 with the tank. Oil is forced by the pump through a pipe 82 to a manifold (Fig. 15) comprising a tube 28 and ends 29 and secured by bracket 29a to the underside of the table 32. Other pipes not shown are connected with this manifold and conduct oil to moving parts of the machine. The excess of lubricating oil collects on the bottom of the base 30 and returns through an opening 77a to the tank 77. Oil entering the pump 73 first passes through a screen or filter not shown.

Referring to Fig. 5, the lubricating oil tank 77 is located in front of a large tank T which comprises portions of the base 30a and plates welded thereto as shown in Fig. 68. The tank T is filled with hydraulic fluid through an opening closed by a plug 703. The level of oil can be observed through a sight glass 701 retained by a ring 702. Drainage of the tank can be effected by removal of one or both the plugs 703. A motor M operates a gear pump P which withdraws oil from the tank through a filter 704 connected with the pump inlet pipe 705. The pump outlet pipe 706 (Fig. 66) is connected with the hydraulic system (Fig. 70) in a manner to be described and also with a pressure relief valve PRV which, when a certain pressure is exceeded, causes the excess to return through pipe 707 to the tank T.

Referring to Fig. 70, pipe 706 is connected with valves F and D. Valve D effects the distribution of pressure fluid to one of the pipes 710 and 711 connected respectively with the ends of the servo cylinder 121 and the connection of the other pipe with drain EX for causing movement of piston 118 in such direction that the cam roller 135b will immediately enter a crossover groove of a cam when the roller 135b arrives at the entrance to this groove. Valve D is controlled by cam 13 which engages the roller 41a (Figs. 14 and 21), said roller being urged toward the cam by a

11

spring not shown in the housing of the valve D. Valve D is so controlled as to effect reversal of connections in advance of arrival of roller 135b at the entrance to a cross over groove.

Valve F has two positions. Solenoid VS3 actuates it into a first position for connecting pipe 706 with pipes 720 and 721 with drain EX. Solenoid VS4 actuates it into a second position for connecting pipes 706 and 721 and to connect pipe 720 with drain. The second position of valve F causes right movement of the piston 323 which effects indexing of the turret. At the end of indexing, piston 323 has moved right to uncover a port 271p in cylinder 271, thereby connecting pipe 721 with check valve 135c and pipe 735 connected with pipe 723. Pipe 720 is connected by a check valve 722 and pipe 723 with the pressure inlet of valve B.

Valve B has two positions, one for connecting pipe 723 with pipe 724 connected to the lower end of cylinder 37 and pipe 725 with pipe 726, and a second position for connecting pipe 723 with pipe 725 and pipe 724 with pipe 726.

Valve E has two positions. When solenoid VS1 is energized, valve E connects pipe 725 with pipe 736 connected with the upper end of cylinder 37. When solenoid VS2 is energized pipes 725 and 736 are connected with drain EX.

Valve A has two positions for connecting pressure line 730 with either of two pilot lines 731, 732 for operating valve B into its respective positions. When the shuttle moves up a certain distance, rod 21 is lifted and valve A operates to condition valve B for passing pressure fluid to the lower end of cylinder 37 so that piston 15c moves up and the shuttle moves down. When the shuttle has moved down a certain distance, rod 21 moves down to reverse valve A which reverses valve B and the piston 15c moves down and the shuttle moves up.

Valve C has two positions. A spring (not shown) actuates valve C into position for blocking connection of pipe 726 with drain EX. When indexing is completed, switch LS5 is closed to energize solenoid VS5 which actuates valve C into position for connecting pipe 726 with drain EX. During normal reciprocation of the shuttle, energization of solenoid VS5 is maintained by other means to be described.

The control of the valve solenoids VS1 through VS5 will be described later with reference to Fig. 72 which shows certain counter switches marked CS1, CS2, CS3 and CS4. The control of the counter switches will now be described with respect to Figs. 53 through 63. The front frame 32 supports a plate 486 to which are attached counters C1, C2, C3 and C4, and counter switches CS1, CS2, CS3 and CS4 and a bracket 497 at the top and three brackets 482. The bracket 497 and the three brackets 482 support a shaft 483 which is operated by handle 503 attached to a crank lever 501 which a clamp screw 502 connects with the shaft. A detent ball 504 urged down by a spring 505 into a socket provided by the bracket 497 retains the lever 501 in a non-operating position. By turning the handle 503 in the proper direction, the counter is reset. To effect this, the shaft 483, is connected by gears 516 and 515 with a reset shaft 514 of each counter. The counter wheels 550, which are reset to zero by shaft 514, count up from zero. Counter wheels 551 each adjustably connected with a wheel 550 count down as the wheels 550 count up. When wheels 550 are at zero the wheels 551 are manually set to indicate a pre-

12

determined number, for example, 144 (Fig. 73). When wheels 550 have counted up to that number the wheels 551 have counted down to zero. Unit wheel 550 adds one and unit wheel 551 subtracts one for each swing of the shaft 5 and cam 13 which, as shown in Fig. 56, engages a roller 509 pivotally supported by a screw 511 carried by a lever 506 pivotally supported by a screw 504 attached to bracket 38. Screw plug 476 retains a spring 479 which pushes down upon a plunger 480 whereby the roller 509 is urged against the cam 13. Lever 506 is connected by link 493 and screw 492 with a bar 485 having notches 485a each wider than a pin 464. There are four notches 485a respectively receiving four pins 464 respectively attached to four levers 467 drivingly connected with the oscillatable counter shafts 468 of the counter. The pins 464 are urged against the upper sides of the notches 485a by springs 476 each connected at one end with a stud 477 attached to the bar 485 and connected at the other end with a thick washer 472 which, as shown in Fig. 58, is carried by the pin 464. As shown in Fig. 57, the bar 485 is guided by brackets 487 and cover plates 484.

When the counter wheels 550 have counted up to a number (for example, 149 in Fig. 73) which is the same as that which had been indicated by the wheels 551 when wheels 550 were at zero, the wheels 551 all indicate zero; and notches 552 therein are in alignment thereby permitting rollers 553 (Figs. 74, 75) to move to 553' (Fig. 75) under the action of a spring (in the counter operated switch, CS4 for example) which urges its plunger 519a up against lever 554 and causes counterclockwise rotation of a shaft 555 (Fig. 75) supporting the lever 554 and connected by gears 556 and 557 with a shaft 558 carrying a yoke lever 559 carrying a rod 560 supporting all the rollers 553. Since all of the notches 552 are in alignment at 553' when the counter counts out the counter controlled switch which is open before the counter has counted out (to number 144, for example) is permitted to close for a purpose to be described. For reasons to be explained, it is necessary that the counter controlled switch remain closed during two successive counts. Therefore, the notch 552 of the units digit wheel 551 is wide enough to allow the counter controlled switch to remain closed for two counts. Each counter switch is housed in a case 519 (Fig. 63) supported by a bracket 518 attached to the plate 486.

Crank handle 503 can be turned only in one direction to turn the wheels 513 back to zero because if an attempt were made to turn the handle in the opposite direction rotation of shaft 483 in the improper direction, which should be counterclockwise in Fig. 61, would be prevented by reason of the engagement with the ratchet 509 connected with shaft 483 by a pawl 489 pivotally supported by a bracket 498 and by a pin 489a and urged clockwise by a spring 489b. The counter mechanism is housed within a case 466, which, as shown in Fig. 59, is hinged connected with the front frame 32 by hinge pins 510. Fig. 55, which is a continuation of the left hand portion of Fig. 53, shows that case 466 is provided with a lug 466a having a notch 466b which receives a latch 517 pivotally supported by the front frame 32.

Referring to Figs. 70 through 72, a three phase line L is connected by main switch 599 and by a relay switch having a coil H and contacts Hc with a pump motor M. Switch S connects two wires of line L with the primary p of a trans-

former T having a secondary S which is connected through fuses with wires 600 and 601. Wire 601 is connected with wire 602 by a starting switch 603 or by contacts Hc' with a wire 602. A series circuit connects wires 600 and 602 with magnet coil H, the energization of which closes contact Hc and Hc', two overload circuit breakers 604 under control by heating elements 605 in the motor circuit, a switch 606 which opens when the wire breaks and a stop switch 607. To start the pump motor, the switch 603 is closed, thereby energizing coil H which closes contacts Hc and Hc'. The pump motor will run so long as the last-mentioned series circuit is closed. The pump motor can be stopped by opening switch 607 or by opening switch 606 when the wire breaks or by an overload on the motor which causes one or both of the switches 604 to open.

The control circuit includes five limit switches, namely: LS1 which is operated when the shuttle is in the center of its vertical stroke which position it occupies when the turret is indexed; LS2 which is closed each time the turret indexes to present a transfer cam to the shuttle oscillating cam follower; LS3 which is closed momentarily when the turret indexes to the position for presenting the transfer cam 274 (Fig. 69) to the follower roller 135b, this being the final indexing when the stator is completely wound; LS4 which is closed each time the shuttle is a short distance above the center of its stroke; and LS5 which is closed at the end of indexing and is opened when piston 323 is returned preparatory to the next indexing. Referring to Fig. 52, rod 323 carries a pin 323b which at the end of indexing will be located at 323b' and will close switch LS5 by engaging and moving its operating lever 323c.

Referring to Fig. 53, counter C1 is set to count out at a number corresponding to twice the number of windings or shuttle passes required to wind coil No. 1. In other words, it counts out at the end of winding coil 1. Counter C2 is set to count out at a number equal to twice the number of windings or shuttle passes required for coil 2, plus the number for which counter C1 was set. Counter C3 is set to count out at a number corresponding to twice the number of windings required for coil 3 plus the number at which counter C2 was set. Counter 4 is set to count out at a number corresponding to twice the number of windings required for coil 4 plus the number at which counter C3 was set. When these counters count out or come to the set number, they cause the closing of the switches CS1, CS2, CS3 and CS4 respectively. Before the counters start to count their wheels 550 are reset to zero and their wheels 551 are set to the numbers which wheels 550 are to indicate when the counters count out. As stated before, when wheels 550 indicate these numbers, wheels 551 will indicate zero.

An unwound stator is placed in the machine and clamped upon the workholder and the automatic cycle which had ended with the shuttle down and solenoid VS3 energized, is ready to begin. It is started by closing the starting cycle switch 608 in circuit #1. This energizes the relay magnet coil CR1 which closes contacts CR1-C1 around the start switch 608 which need be closed only momentarily. Circuit #1 is then completed and remains so until normally closed contacts CR2-C1 or CR4-C1 are opened. The completion of circuit #1 effects closing of circuit #2 by closing contacts CR1-C3 which are closed when coil CR1 is energized. This effects

energization of the solenoid VS1 and valve E (Fig. 70) then connects pipes 725 and 736 and pressure fluid flows through valve F, pipes 720, 723, valve B and pipes 725 and 736 to the upper end of cylinder 37 and piston 15c moves downward, thereby causing the shuttle to move up.

When the shuttle reaches the center of its first up-stroke, switch LS1 is closed, thereby completing circuit #3 which includes relay magnet coil CR2, a pair of contacts CR1-C2 (closed when circuit #1 was completed) and switch LS1. Coil CR2 is energized and normally closed contacts CR2-C1 in circuit #1 are opened, thereby deenergizing magnet coil CR1 and opening all of the CR1 contacts. Therefore, circuit #1 is cancelled. The energization of coil CR2 causes contact CR2-C2 in circuit #4 to be closed, thereby energizing solenoid VS4 and separating contacts CR2-C3 in circuit #6, thereby deenergizing solenoid VS3. Energization of coil CR2 causes contacts CR2-C4 in circuit #5 to open to deenergize solenoid VS5 whereupon valve C blocks escape to drain and piston 15c is hydraulically locked in mid-down stroke position and the shuttle in mid-up stroke position. Valve F then connects pipe 720 with drain and connects pressure line 706 with the left end of turret index cylinder 271 and the turret indexes from transfer cam 274 (Fig. 69) to coil #1 winding cams 275. After the turret piston 323 has moved right in Fig. 70 to cause an index, it uncovers a port 271p which connects the pressure line 706 to the pressure port of valve B through pipe 735 and pipe 723. Valve B at this time directs the line pressure through pipe 725 to the pressure port of valve E and through valve E to the top of the shuttle cylinder 37. The piston 15c moves down and the shuttle moves up (as indicated by arrow 1 between cams 275) from its mid-position. As the shuttle moves away from its mid-position, switch LS1 is opened, coil CR2 is deenergized and circuits #3 and #4 are opened and circuits #5 and #6 are closed. When circuit #5 is completed, solenoid VS5 operates valve C to connect pipe 726 with drain EX. When circuit #6 is completed and valve solenoid VS3 is energized, this solenoid causes an operation of valve F to direct line pressure through pipes 720 and 723 to valve B and to the opposite end of turret index cylinder, thus restoring the indexing mechanism to position for the next index.

The shuttle continues its upward movement and so moves rod 21 and cam 83 and the actuator of the pilot valve A, that reversal of valve B is effected so that the line pressure is directed to the bottom of the shuttle cylinder 37, thus moving the piston 15c upwardly and the shuttle downwardly. The cam 83 effects operation of valve B to reverse it so that it directs pressure to the top of the shuttle cylinder to move the piston 15c down and the shuttle up.

When the predetermined number is reached by counter C1, counter switch CS1 is closed and coil CR3 is energized. This happens in the center of the last stroke of the shuttle with the shuttle coming down as represented by arrow 2 between cams 275 (Fig. 69). Since at this time switch LS1 is closed, circuit #3 is closed and coil CR2 is energized. This causes circuit #4 to be completed and circuits #5 and #6 to be interrupted and valve solenoid VS4 is energized, thereby causing valve F to direct the line pressure to the turret index cylinder, thereby causing an index from coil #1 winding cams 275 (Fig. 69) to transfer cam 276. When the index is completed, the line pressure passes through

the turret index cylinder to the shuttle cylinder, thereby moving the shuttle downwardly off center as indicated by arrow 2 above cam 276 (Fig. 69) and opening the switch LS1.

When switch LS1 opens, circuits #3 and #4 are cancelled and circuits #5 and #6 are closed again. The shuttle moves down and then half way up as indicated by arrow 3 above cam 276 (Fig. 69). Since switch CS1 is still closed and switch LS1 is closed when the shuttle is half way up, a second index will take place from the transfer cam 276 to the #2-coil-cams 277. Then the shuttle resumes its upward movement as indicated by arrow 3 between cams 277. The shuttle then continues to reciprocate until when counter C2 counts out, the shuttle stops at middle of the last down stroke as indicated by arrow 4. The turret indexes from cams 277 to transfer cam 301, shuttle down-movement is resumed; and the shuttle stops mid-way of the next up movement as indicated by arrow 5 above cam 301. Then there is a second index from cam 301 to #3-coil-cams 297 and the shuttle resumes upward movement as indicated by arrow 5 between cams 297. The cycle is repeated and when counter C3 counts out, the shuttle stops mid-way of the last down stroke as indicated by arrow 6 between cams 297 and there is an index from cams 297 to transfer cam 295, resumption of down-stroke, stopping of next up-stroke mid-way as indicated by arrow 7 above cam 295, an index from cam 295 to #4 coil-cams 294 and resumption of up-stroke as indicated by arrow 7 between cams 294. When counter C4 counts out, the last down stroke for winding coil #4 is stopped mid-way as indicated by arrow 8 between cams 294 and there is an index from cams 55 to transfer cam 274 and the down stroke is resumed as indicated by arrow 8 above cam 274.

During this final index switch LS3 is momentarily closed thereby completing circuit #8 to effect the energization of valve solenoid VS2. Valve E is then operated to connect valve B with drain to the oil storage tank connected with the pump. Because the shuttle is moving downwardly nothing happens. But, when valve B is reversed by valve A and tries to supply a line pressure to the shuttle cylinder, this pressure is diverted to the drain by valve E. The shuttle therefore comes to rest in its down position. The wound stator is removed and replaced with an unwound stator and the start cycle button is again operated to repeat the cycle.

A safety circuit #9 is provided. In case of failure to index from a transfer cam to a coil winding cam due to failure of switch LS1, the cam follower would encounter no cam and would get out of control and damage to the machine would probably result. This condition would always occur when a transfer cam is in the operative position and while the next movement of the shuttle would be upward. Circuit #9 is closed because switches LS2, LS4 and contacts CR3—C2 are closed concurrently. Contacts CR3—C2 are closed because one of the counter switches is connecting relay coil CR3 with the current source at this time. Switch LS2 is closed at this time by cam 310 which closes LS2 when a transfer cam is in operative position. Switch LS4 is closed when the cam follower arrives above the level where indexing should have occurred. When circuit #9 is closed, relay coil CR4 is energized to effect closing of the contacts CR4—C2 in circuit #8, thereby energizing solenoid VS2 and causing valve E to divert the pressure to drain thus stop-

ping the machine. In the normal cycle which is taking place, coil CR3 will be deenergized at the time switch LS4 is closed because the counter switch which had closed to energize coil CR3 will then be open because its counter has moved past the second count from its count-out position.

While the embodiment of the present invention as herein disclosed, constitutes a preferred form, it is to be understood that other forms might be adopted, all coming within the scope of the claims which follow.

What is claimed is as follows:

1. A stator winding machine comprising a fixed stator core holder, fixed wire anchors, an axially movable and rotatable shuttle having passages through which wires are threaded and secured to the anchors, shuttle reciprocating means which axially moves the shuttle through the stator core, means for rotating the shuttle while outside of the core in order to form the end loops of the coils wound on the core, means determining the angle of rotation and including a cam follower operatively connected with the shuttle and a series of cams which are moved in sequence into position to receive the cam follower, winding turn counting means, and means under control by said turn counting means for positioning the cams in succession to the cam follower.

2. A stator winding machine comprising a fixed stator core holder, fixed wire anchors, an axially movable and rotatable shuttle having passages through which wires are threaded and secured to the anchors, means for axially moving the shuttle through the stator core, means for effecting reversal of operation of said first means upon completion of a shuttle stroke required for a particular coil, means for variably controlling the second means in order to vary the timing of stroke reversal, means for rotating the shuttle while outside of the core in order to form the end loops of the coils wound on the core, means determining the angle of rotation and including a cam follower operatively connected with the shuttle and a series of cams which are moved in sequence into position to receive the cam follower, winding turn counting means, and means under control by said turn counting means for positioning the cams in succession to the cam follower and for conditioning the third mentioned means to obtain the timing of stroke reversal that is required by the cam then cooperating with the cam follower.

3. A stator winding machine comprising a fixed stator core holder, fixed wire anchors, an axially movable and rotatable shuttle having passages through which wires are threaded and secured to the anchors, means for axially moving the shuttle through the stator core, means for effecting reversal of operation of said first means upon completion of a shuttle stroke required for a particular coil, means for variably controlling the second means in order to vary the timing of stroke reversal, means for rotating the shuttle while outside the core to form the end loops of the coils wound on the core, means for determining the angle of rotation and including a cam follower operatively connected with the shuttle and a series of cams which are moved in sequence into position to receive the cam follower, said series comprising winding cams arranged in pairs, the cams of each pair being spaced apart, the number of pairs equaling the number of coils per stator pole, and said cam series comprising transfer cams intermediate the pairs of wind-

ing cams, a rotatable turret supporting said cams, a turret indexing means, winding turn counting means, a control device which is rendered effective when the shuttle is at mid-stroke position, means under control by the turn counting means and the control device for effecting operation of the indexing means, means for arresting movement of the shuttle during indexing and means operated by the indexing means for conditioning the third mentioned means to obtain the timing of stroke reversal that is required by the cam then cooperating with the cam follower.

4. A stator winding machine comprising a fixed stator core holder, fixed wire anchors, an axially movable and rotatable shuttle having passages through which wires are threaded and secured to the anchors, a hydraulic servomotor for axially moving the shuttle through the stator core and comprising a cylinder and a piston therein connected with the shuttle, a valve for controlling admission to pressure fluid to an end of the cylinder and the connection of the other end of the cylinder with drain, valve control means operated by shuttle movement and having a device by which the timing shuttle reversal with respect to shuttle movement can be varied, means for rotating the shuttle while outside of the core in order to form the end loops of the coils wound on the core, means determining the angle of rotation and including a cam follower operatively connected with the shuttle and a series of cams which are moved in sequence into position to receive the cam follower, winding turn counting means, and means under control by said turn counting means for positioning the cams in succession to the cam follower and for adjusting said device to obtain the timing of stroke reversal that is required by the cam then cooperating with the cam follower.

5. A stator winding machine comprising a fixed stator core holder, fixed wire anchors, an axially movable and rotatable shuttle having passages through which wires are threaded and secured to the anchors, a hydraulic servomotor for axially moving the shuttle through the stator core and comprising a cylinder and a piston therein connected with the shuttle, a valve for controlling admission to pressure fluid to an end of the cylinder and the connection of the other end of the cylinder with drain, valve control means including a rotatable and axially movable rod, spaced discs mounted thereon, pins carried by the discs and located in axially aligned pairs parallel to the rod, the pins of each pair differing in length from the pins of the other pairs, members connected with the shuttle and movable between and respectively against the pins of one pair when positioned for engagement by said members, means for rotating the shuttle while outside of the core in order to form the end loops of the coils wound on the core, means determining the angle of rotation and including a cam follower operatively connected with the shuttle and a series of cams which are moved in sequence into position to receive the cam follower, winding turn counting means, and means under control by said turn counting means for positioning the cams in succession to the cam follower and for rotating the rod to position the required pair of pins for engagement by said members.

6. A stator winding machine comprising a fixed stator core holder, fixed wire anchors, an axially movable and rotatable shuttle having passages through which wires are threaded and secured

to the anchors, a hydraulic servo-motor for axially moving the shuttle through the stator core and comprising a cylinder and a piston therein connected with the shuttle, a valve for controlling admission of pressure fluid to an end of the cylinder and the connection of the other end of the cylinder with drain, valve control means including a rotatable and axially movable rod, spaced discs mounted thereon, pins carried by the discs and located in axially aligned pairs parallel to the rod, the pins of each pair differing in length from the pins of the other pairs, members connected with the shuttle and movable between and respectively against the pins of one pair when positioned for engagement by said members, means for rotating the shuttle while outside the core to form the end loops of the coils wound on the core, means for determining the angle of rotation and including a cam follower operatively connected with the shuttle and a series of cams which are moved in sequence into position to receive the cam follower, said series comprising winding cams arranged in pairs, the cams of each pair being spaced apart, the number of pairs equalling the number of coils per stator pole, and said cam series comprising transfer cams intermediate the pairs of winding cams, a rotatable turret supporting said cams, a turret indexing means, winding turn counting means, a control device which is rendered effective when the shuttle is at mid-stroke position, means under control by the turn counting means and the control device for effecting operation of the indexing means, means for arresting movement of the shuttle during indexing and means operated by the indexing means for rotating the rod to position the required pair of pins for engagement by said members.

7. A stator winding machine comprising a fixed stator core holder, fixed wire anchors, an axially movable and rotatable shuttle having passages through which wires are threaded and secured to the anchors, a first hydraulic motor for effecting axial movement of the shuttle through the core, a reversing valve therefor, a second hydraulic motor for effecting rotary movement of the shuttle, a reversing valve therefor, means determining movement of the shuttle comprising a series of pairs of winding cams, the number of pairs being equal to the number of stator pole coils, and transfer cams located respectively between the winding cams, each of said cams having two parallel straight grooves joined by a curved groove, a rotatable turret which supports the cams with their straight grooves all parallel to the direction of axial movement of the shuttle, each pair of winding cams being spaced apart by a vacant zone and the straight grooves of the cams of each pair being in alignment and opening into the vacant zone and each of the transfer cams being located on the same side of the vacant zone having each of its straight grooves opening into the vacant zone, a cam follower connected with the shuttle and received by the grooves of said cams in sequence, means responsive to axial shuttle movement sufficient to carry the follower across the vacant zone into a straight cam groove for causing operation of the second reversing valve whereby, in advance of the ending of the shuttle stroke, the second servomotor urges the follower for entrance into the curved cam groove, means for controlling the first reversing valve to obtain stroke reversal when the follower has entered the curved cam-

groove whereby reverse stroke effects the amount of shuttle rotation determined by the cam, means for variably conditioning the first reversing valve controlling means to effect first servomotor reversal at the time required by the cams, means for indexing the turret and for operating the means for variably conditioning the first reversing valve controlling means, means for preventing rotation of the shuttle while the cam follower is in the vacant zone, coil turn counting means, a control device rendered operative upon arrival of the shuttle at mid-stroke position when the cam follower is in the vacant zone, means under control by the turn counting means and said device when operative for causing the shuttle to stop and for effecting operation of the turret indexing means.

8. A stator winding machine comprising a fixed stator core holder, fixed wire anchors, a shuttle having passages through which wires are threaded and secured to the anchors, a rotatable shaft connected with the shuttle, a shuttle carriage supporting the shaft and shuttle and mounted for movement of the shaft axially, means for moving the carriage including a first hydraulic motor having a cylinder and a piston, means for rotating the shaft including a second hydraulic motor having a cylinder and a piston, means determining movement of the shuttle comprising a series of pairs of winding cams, the number of pairs being equal to the number of stator pole coils, and transfer cams located respectively between the winding cams, each of said cams having two parallel straight grooves joined by a curved groove, a rotatable turret which supports the cams with their straight grooves all parallel to the direction of axial movement of the shuttle, each pair of winding cams being spaced apart by a vacant zone and the straight grooves of the cams of each pair being in alignment and opening into the vacant zone and each of the transfer cams being located on the same side of the vacant zone having each of its straight grooves opening into the vacant zone, a cam follower connected with the shuttle shaft and received by the grooves of said cams in sequence, means for indexing the turret including a third hydraulic motor having a cylinder and a piston, a valve D for controlling the flow of pressure fluid into an end of the third motor cylinder while connecting the other end with drain and vice versa, a mechanism operated by the first motor for causing valve D to reverse the connection to the third motor cylinder after the cam follower has passed the vacant zone and has entered a straight cam groove whereby, in advance of the ending of the shuttle stroke, the second motor urges the follower for entrance into the curved cam groove, a valve B for controlling flow of pressure fluid into an end of the first motor cylinder while providing a connection between the other end of said cylinder and drain, means for controlling valve B to obtain stroke reversal when the follower has entered the curved cam groove whereby the reverse stroke effects the amount of shuttle rotation determined by the cam, means operated by the turret indexer for adjusting the valve B controlling means to obtain stroke reversal at the time required by the cam engaged by the follower, means for preventing rotation of the shuttle shaft while the cam follower is in the vacant zone, a valve F movable to a first position for connecting a source of fluid pressure with the pressure inlet of valve B and with the indexing motor cylinder to effect

return movement of its piston preparatory to the next indexing operation and also to connect the other end of the third cylinder with drain, said valve F being movable to a second position for blocking connections of the pressure source with the inlet of valve B and for reversing the connections with the third motor cylinder, a solenoid VS3 for moving the valve F to its first position, a solenoid VS4 for moving the valve F to its second position, a valve C for controlling the flow from the drain port of valve B, a spring holding valve C in position to block the drain, a solenoid VS5 for moving valve C to open the drain port, a valve E having a first position for making connection between one end of the first motor cylinder and a distribution port of valve B and having a second position for draining said connection, solenoids VS1 and VS2 for moving valve E to its first and second positions, respectively, a current source, a switch LS3 for connecting solenoid VS2 with the current source when winding is completed whereby the winding cycle stops, a circuit normally connecting solenoid VS3 with the source, a manually controlled start cycle relay CR1 for connecting solenoid VS1 with the source, an index control relay CR2, a plurality of turn counters and a relay CR3 controlled thereby, parallel switches respectively controlled by the counters, and each effecting operation of relay CR3 when closed, a circuit for connecting the index control relay CR2 with the source including a switch LS1, means for closing switch LS1 to effect indexing when the cam follower is in the vacant zone, means operated by relay CR2 for de-energizing solenoids VS3 and VS5 and energizing solenoid VS4 in order to block the first motor piston during indexing, means operable at the end of indexing for energizing solenoid VS5 and for effecting a movement of the first motor piston sufficient to effect opening of switch LS1 thereby deenergizing relay CR2 and solenoid VS4 and reenergizing solenoid VS3 whereby reciprocation of the shuttle continues until the next polar coils are completed.

45 9. A machine according to claim 8 having a safety circuit which includes a relay CR4, contacts of relay CR3 when closed, a switch LS2 which closes when a transfer cam is presented by the turret to the cam follower, and a switch LS4 which closes when the shuttle carriage moves the cam follower beyond the vacant zone of the turret, and contacts of the relay CR4 which close when that relay is energized to connect solenoid VS2 with the current source.

55 10. A stator winding machine comprising a fixed stator core holder, fixed wire anchors, an axially movable and rotatable shuttle having passages through which wires are threaded and secured to the anchors, a hydraulic servo-motor for axially moving the shuttle through the stator core and comprising a cylinder and a piston therein connected with the shuttle, a valve for controlling admission of pressure fluid to an end of the cylinder and the connection of the other end of the cylinder with drain, valve control means including a rotatable and axially movable rod, spaced discs mounted thereon, pins carried by the discs and located in axially aligned pairs parallel to the rod, the pins of each pair differing in length from the pins of the other pairs, members connected with the shuttle and movable between and respectively against the pins of one pair when positioned for engagement by said members, means for rotating the shuttle while outside the core to form the end loops of the coils

21

wound on the core, means for determining the angle of rotation and including a cam follower operatively connected with the shuttle and a series of cams which are moved in sequence into position to receive the cam follower, said series comprising winding cams arranged in pairs, the cams of each pair being spaced apart, the number of pairs equalling the number of coils per stator pole, and said cam series comprising transfer cams intermediate the pairs of winding cams, 10 a rotatable turret supporting said cams, a turret indexing means, actuating means therefor, means for controlling the operation of said actuating means including a control device operable when the shuttle is at mid-stroke position, means 15 for arresting movement of the shuttle during the

5

indexing operation, and means operated by the indexing means for rotating the rod to position the required pair of pins for engagement by said members.

22

10

indexing operation, and means operated by the indexing means for rotating the rod to position the required pair of pins for engagement by said members.
